UNITED STATES PATENT OFFICE.

WILLIAM B. GARRETT, OF ASHTON, ILLINOIS, ASSIGNOR OF ONE-HALF
TO FRANCIS E. DRESSER AND ANDREW B. ELMER, OF ROCHELLE,
ILLINOIS.

ELECTRIC SIGN.

No. 849,226.

Specification of Letters Patent.

Patented April 2, 1907.

Application filed May 28, 1906. Serial No. 319,210.

To all whom it may concern:

Be it known that I, WILLIAM BROWN GARRETT, a citizen of the United States, residing at Ashton, in the county of Lee and State of Illinois, have invented certain new and useful Improvements in Electric Signs, of which the following is a specification.

The object of this invention is to construct an electric sign composed of incandescent lamps arranged in certain order and in which the current-switching mechanism is arranged in like order, so that by the employment of movable contact-points, being a part of the switching mechanism, the letters or words to be displayed can be outlined on the switching mechanism.

In the accompanying drawings, Figure 1 is a face representation of my improved sign. Fig. 2 is a rear face view of the sign and an inner face view of the stationary section of the circuit-closing mechanism and in which the wires connecting the sign and section are shown. Fig. 3 is a transverse section through the sign and circuit-closing mechanism. Fig. 4 is a transverse section through the movable section of the current-closing mechanism. Fig. 5 is an outstretched view of the movable section of the circuit-closing mechanism, showing its outer face.

The sign proper consists of the frame 1, within or in connection with which are arranged in this instance five series or rows of incandescent electric lamps 2, 3, 4, 5, and 6, which are nestled closely together and the lamps of one series located midway between the lamps of the next series in order that the direct lines of the lamps be diagonal to the length of the sign as distinguished from those arranged in lines at right angles thereto.

All of the lamps on the back of the frame are electrically connected to the main return or common wire 7, which has a connection with the generator 8 in the usual manner. At Fig. 2 I have shown the individual wiring for each lamp; but as it would confuse the drawings to give a reference-numeral to each wire I will number the wires for the lamps indicating the letter capital "A," and the lamps for outlining the letters are marked 9 to 19, inclusive, as shown at Figs. 1 and 2.

The individual wires for the lamps 9 to 19, inclusive, are marked 20 to 30, inclusive and respectively. The electric switching mechanism in this instance comprises a rotatable

metallic drum 53, provided with holes arranged in its surface corresponding in number and arrangement with the lamps of the frame. This drum in this instance has a double set of holes, each corresponding in number and arrangement with the lamps of the frame; but as it is a duplication a description of the arrangement for indicating the letter "A" of the sign proper will suffice. The holes are arranged in lengthwise series 31, 23, 30, 24, and 35, corresponding to the rows 2 to 6 of the lamps, and the series of holes of a row are arranged in the same offset relation as the lamps. In some of the holes are arranged the pins 36, 37, 38, 39, 40, 41, 42, 43, 44, 45, and 46, as shown at Fig. 5, which correspond with the lamps 9 to 19, inclusive and respectively.

At one end of the drum is located two insulating-strips 47 and 48, leaving the metallic surfaces 49 and 50 exposed. A spring 75 or contact-arm 65 bears, as shown in the drawings, against the metallic surfaces 49, and this arm is electrically connected to the generator 8 by the wire 51. A stationary portion 52, a part of the current-switching mechanism, is located adjacent to the drum 53, having its inner surface conforming to the outer surface of the drum. This stationary portion 52, which is of insulating material, supports contact-plates arranged in rows and offset to correspond to the lamps in the frame, also with the holes in the drum. It will only be necessary to indicate such plates required to indicate the letter "A," such plates being marked 54, 55, 56, 57, 58, 59, 60, 61, 62, 63, and 64, as shown at Fig. 2, which corresponds with the lamps 9 to 19, inclusive and respectively.

The wires 20 to 30, inclusive, connect with the contact-plates 54 to 64, inclusive and respectively, as shown at Fig. 2, so that each of the several lamps indicating the letter "A" is electrically connected with its corresponding contact-plate, which can readily be located at Fig. 2 of the drawings. The drum 53 is located with relation to the stationary portion 52 of the current-switching mechanism, so that the pins 36 to 46, inclusive, will rest in contact with the plates 54 to 64, inclusive and respectively—that is, the arrangement of the contact-plates and the holes in one-half of the drum are the same as the arrangement of lamps, so that if pins

were placed in all the holes of the half of the drum and they rested in contact with their respective plates and the arm 45 being in contact with the projection 49 all of the 5 lamps on the frame would be in electric circuit with the generator and would be lighted, so far as described, only the pins, plates, and lamps for the letter "A" will be included in the electric circuit. The object in arranging the 10 holes in the same arrangement as the lamps is to enable any letter or word to be set up and properly outlined on the drum.

By providing the drum with a double arrangement of holes two sections can be set up, 15 and by intermittently revolving the drum the projection 50 will be brought in contact with the arm 65, thereby closing the circuit through the drum, and its other set of pins will be brought in contact with the plates of 20 the stationary portion or such of them as is necessary to indicate the proper letter or sentence. By employing the projections 49 and 50 and the insulating-strips 47 and 48 the circuit through the drum will be held open 25 until the drum has rotated sufficiently to place the pins in contact with the proper plates, thereby illuminating the letter, word, or sentence at a single flash. Another object in making the drum double is to enable one 30 section to be set up while the other section is being flashed. It is evident that the drum may contain more than two sections or series of holes, which will enable a greater number of sentences to be flashed at a single revolution. 35

I have not deemed it necessary to show means for intermittently rotating the drum, as various devices can be employed. In the drawings I have shown five series of holes 40 but seven or nine make a better arrangement, and any number of rows I desire to come within the scope of my invention.

At Fig. 1 the shaded lamps outline the letters "A," "B," and "C," and Fig. 5 one set of 45 pins outline the same letter and the other set outline the letters "D," "E," and "F." It is to be understood that the frame containing the lamps can be lengthened to contain sufficient lamps to indicate the required sentence. It 50 is also intended to make the drum and stationary portion 52 of smaller dimension than the sign, but having the arrangement of holes and plates corresponding to the arrangement of the lamps.

55 I claim as my invention—

1. An electric sign, comprising a plurality of incandescent lamps closely arranged in parallel rows, a plurality of contact members, individual circuit connections between 60 said lamps and members, a movable support provided with a plurality of seats having the same relative arrangement as said lamps, and contact-points removably mounted in said seats and adapted to be brought into engagement with the contact members. 65

2. An electric sign, comprising a plurality of incandescent lamps closely arranged in parallel rows, a plurality of contact members, individual circuit connections between said lamps and members, a movable support provided with a plurality of seats having the same relative arrangement as said lamps, 70 contact-points removably mounted in said seats and adapted to be brought into engagement with the contact members, and a return-circuit common to all said contact-points. 75

3. An electric sign, comprising a plurality of incandescent lamps closely arranged in parallel rows, a plurality of contact members, 80 individual circuit connections between said lamps and members, a movable support provided with a plurality of seats having the same relative arrangements as said lamps, contact-points removably mounted in said 85 seats and adapted to be brought into engagement with the contact members, and means for completing the circuits through a group or groups of the lamps when the points and members are brought together. 90

4. In an electric display apparatus, a plurality of closely-arranged incandescent lamps, a plurality of contact members having the same relative arrangement as said lamps, individual circuit connections between said 95 lamps and members, a movable support, and a plurality of seatable contact-points carried by said support and having the same relative arrangement as said lamps and contact members, substantially as described. 100

5. In an electric display apparatus, a plurality of closely-arranged incandescent lamps, a plurality of contact members having the same relative arrangement as said lamps, individual circuit connections between said 105 lamps and members, a movable support, a plurality of seatable contact-points carried by said support and having the same relative arrangement as said lamps and contact members, a source of electric supply, and a return-circuit common to all said contact-points. 110

6. An electric sign, comprising a plurality of incandescent lamps closely arranged in parallel rows, a curved support, a plurality of exposed contact members mounted on said 115 support, individual circuit connections between said lamps and members, a rotatable drum disposed opposite and closely adjacent the concave face of said curved support, said drum being provided with a plurality of seats 120 having the same relative arrangement as the lamps and contact members, contact-points removably mounted in said seats, a source of electric supply, and a return-circuit common to all said contact-points. 125
